Primary Examiner — William Phillip Fletcher, III(74) *Attorney, Agent, or Firm* — Andrew M. Calderon;
Roberts Mlotkowski Safran & Cole, P.C.(57) **ABSTRACT**

The solution of the problem is arrived at through the following steps:

- applying liquid resin to the top side,
- drying the resin,
- pressing the construction plate under the influence of temperature, so that the resin at least partially melts, wherein the pressing may be performed in a continuous press.

METHOD FOR SEALING A BUILDING
PANEL

FIELD OF THE INVENTION

The invention relates to a process for sealing a construction plate of wood or of a wood material having a top side and a bottom side.

BACKGROUND DESCRIPTION

Construction plates may be floor boards, such as parquet; sheathing boards, or sheets for furniture building. These plates are made of solid wood, especially doweled and glued wood, or they may consist of a core of a wood material such as MDF, HDF (medium-density fiberboard, high-density fiberboard) or floor plates onto which a real wood veneer is cemented. OSB boards (Oriented Strand Boards) are the principal sheathing boards used.

The surfaces of these plates must be sealed to protect them from environmental influences. Penetration of moisture in particular must be prevented for floor boards. The surface of the board is often painted for that purpose. Paint is relatively soft, and the paint coat is subject to wear, especially in parquet floors, so that the floor must be resealed often. In closed spaces, that is linked with unpleasant features, as the old coat of paint must be sanded off before a new one can be applied. The fine sanding dust deposits everywhere, and then must be tediously removed.

Laminated panels are sealed with a coating of synthetic resin. To produce laminated panels, a paper sheet printed with a pattern is laid on a carrier board of MDF, HDF or chipboard, on which has been laid an overlay, a layer of synthetic resin or a paper layer soaked with synthetic resin. Then the board is pressed, with heating, so that the overlay, including the paper layer, bonds to the surface of the board. For floorboards, corundum particles are incorporated in the finished overlay to increase resistance to wear. Then individual panels are sawed out of the boards so produced.

A resin is not only less expensive than paint, but also harder. Placing the paper sheet or a ready-made overlay onto the top side of the plate of wood material must be done carefully. Handling of the very thin layers is complicated and requires precisely operating machines so as to make sure that only one individual layer of the overlay is lifted from a stack. For a laminated plate, the bottom side must be given an "undercoat" that compensates for the tensile stresses produced on the plate core by the decorated layer in order to prevent bending of the plate, and especially of the panels sawed out later, in the longitudinal direction.

A parquet structure is known from EP B1-0 560 870, in which a filler resin or paint is impregnated into the interior and into the intermediate spaces of the vertical grain of the wood, under the varnish layer which forms the surface coating, so that the amount of the paint is several times greater than the amount of the parquet varnish. After the filler resin has penetrated in, the boards are preheated. After cooling they absorb the resin down to a sufficient depth to form a "barrier layer" which prevents the expensive varnish penetrating in too deeply when the parquet is later sealed. This measure provides harder surfaces than the usual sealed parquetry with the same consumption of varnish.

It is known from DE C2-37 35 368 that a powdered resin layer can be scattered on a plate of material and then pieces of

2

inlay can be placed on that. Then the powder layer is hot-pressed to melt the resin and bond it to the plate.

SUMMARY OF THE INVENTION

5

Based on that statement of the problem, a process will be described for sealing a construction board of wood or a wood material with a real wood surface, with which the wear-resistant surface known for laminated plates can be attained, 10 but which is simpler and can be carried out faster.

DETAILED DESCRIPTION OF EMBODIMENTS
OF THE INVENTION

15 The solution of the problem is arrived at through the following steps:

- a) applying liquid resin to the top side,
- b) drying the resin,
- c) pressing the construction plate under the influence of 20 temperature, so that the resin at least partially melts, wherein the pressing may be performed in a continuous press.

The liquid resin can be rolled on, sprayed on, or poured on. It is considerably easier to handle than a premade resin layer. If the resin layer is applied correspondingly thick, the surface 25 hardness known for laminated plates is produced. Thus it is possible to provide a construction plate which combines the positive properties of solid wood or veneered wood material with the positive properties of a laminate. The considerably harder resin gives very high wear resistance, which can be 30 increased even more by mixing corundum particles into the liquid resin, or by scattering them on it.

Use of appropriately polished press surfaces in the press can produce degrees of gloss on pressing the construction plate. A press plate polished to a high gloss results in highly 35 glossy or even reflective surfaces. That can generate particularly beautiful visual effects. An OSB plate can be smoothed to eliminate unevennesses in the surface before application of the resin coating.

The bottom side of the construction plate can be sealed in 40 the same manner. Then OSB plates in particular, which exhibit very high strength, can be used as concrete form sheets. Not only does the synthetic resin layer prevent penetration of moisture into the form sheet, but it also increases its life because of the hardness of the surface.

45 The resin can be applied in multiple layers, with each layer being dried before the next is applied.

It is preferable for the resin to be a synthetic resin, especially a melamine resin.

The resin can be stained to produce special visual effects. A 50 color layer can be applied between the resin layers on the top or bottom sides. The color layer can be printed. That has the advantage that the appearance can be improved. For instance, an oak or rosewood pattern, with the appropriate grain and color, can be applied to a pine veneer, increasing the value of 55 the real wood surface.

A relief matching the pattern (of the wood grain) can be embossed in the resin layer on pressing so as to match the feel of the sealed surface to that of the unsealed wood.

Other fillers can also be mixed into the resin layer, or 60 sprinkled onto individual layers. Application of such a layer to the bottom side can, for instance, improve the impact sound characteristics of a floor board.

It is preferable to coat the top and bottom sides at the same time. Not only does that provide completely new and 65 improved product properties, but it also simultaneously makes a substantial reduction in the production cost of the construction plate.

The invention claimed is:

1. A process for sealing a construction plate of wood or a wood material, having a top side and a bottom side, with the following steps:
  - applying multiple layers of a liquid resin on the top side, drying the resin,
  - pressing the construction plate under the influence of temperature so that the resin at least partially melts, wherein the pressing is performed in a continuous press, and embossing a relief matching a pattern of a wood grain into the resin layer on pressing.
2. The process according to claim 1, further comprising the following steps:
  - application of the resin to the bottom side,
  - drying the resin,
  - pressing the construction plate under the influence of temperature so that the resin at least partially melts.
3. The process of claim 2, further comprising mixing fillers into the resin on the bottom side for improving impact sound characteristics of a floor board made from the plate.
4. The process according to claim 1, wherein an applied one of the multiple layers is dried before a next one of the multiple layers is applied.
5. The process according to claim 1, wherein the resin is a synthetic resin.
6. The process according to claim 5, wherein the synthetic resin is a melamine resin.
7. The process according to claim 1, wherein the resin is stained.
8. The process according to claim 1, further comprising applying a color layer between the resin layers.
9. The process of claim 8, wherein:
  - the color layer is printed with a wood grain pattern, and the pressing embosses the relief matching the wood grain pattern into the resin.
10. The process according to claim 1, wherein corundum is mixed into or scattered onto individual layers of the multiple layers.
11. The process according to claim 2, wherein the resin is applied simultaneously on the top side and the bottom side.
12. The process of claim 1, wherein the construction plate comprises solid wood.
13. A process for sealing a plate of wood, the plate having a top side and a bottom side, the process comprising:
  - simultaneously coating the top side and the bottom side with resin;
  - drying the resin;
  - pressing the plate under the influence of temperature so that the resin at least partially melts, wherein the pressing is performed in a continuous press; and
  - applying a color layer between the resin and at least one of the top side and the bottom side,

wherein the color layer is printed with a wood grain pattern and the pressing embosses a relief matching the wood grain pattern into the resin.

14. The process of claim 13, wherein:
  - the resin is stained to produce a visual effect, corundum particles are mixed into or scattered onto the resin, and the plate is solid wood.
15. The process of claim 13, further comprising mixing fillers into the resin on the bottom side for improving impact sound characteristics of a floor board made from the plate.
16. A process for sealing a plate of wood or wood material, the plate having a top side and a bottom side, the process comprising:
  - applying multiple layers of a synthetic liquid resin on the top side, wherein an applied one of the multiple layers is dried before a next one of the multiple layers is applied on the top side;
  - applying multiple layers of the synthetic liquid resin on the bottom side, wherein an applied one of the multiple other layers is dried before a next one of the multiple other layers is applied to the bottom side;
  - pressing, in a continuous press, the plate under the influence of temperature so that the synthetic liquid resin at least partially melts;
  - embossing a relief matching a pattern of wood grain in the synthetic liquid resin; and
  - applying a color layer between the synthetic liquid resin layers on the top side, the color layer being printed with the wood grain pattern, wherein:
    - the synthetic liquid resin is stained to produce a visual effect,
    - corundum particles are mixed or sprinkled onto individual layers of the multiple layers of the synthetic liquid resin on the top side,
    - mixing fillers into the layers of synthetic liquid resin on the bottom side for improving impact sound characteristics of a floor board made from the plate; and
    - the multiple layers of the synthetic liquid resin are applied simultaneously on the top side and the bottom side.
17. The process of claim 16, wherein the applying the color layer is a printing process.
18. The process of claim 17, wherein the plate of wood is OSB and prior to the applying multiple layers of the synthetic liquid resin on the top side and the bottom side, smoothing the OSB to eliminate unevenness.
19. The process of claim 18, wherein the pressing forms a glossy or reflective surface on the plate.
20. The process of claim 19, wherein the synthetic liquid resin is melamine.
21. The process of claim 17, wherein the plate is solid wood.
22. The process of claim 21, wherein the pressing forms a glossy or reflective surface on the plate.
